UNITED STATES PATENT OFFICE

161,376

HANDLE FOR STOVES OR THE LIKE

Kurt Rettich, Grand Rapids, Mich., assignor to
Keeler Brass Company, Grand Rapids, Mich.

Application August 10, 1949, Serial No. 4,396

Term of patent 14 years

(Cl. D81—25)

To all whom it may concern:

Be it known, that I, Kurt Rettich, a citizen of the United States, residing at Grand Rapids, county of Kent, State of Michigan, have invented a new, original, and ornamental Design for a Handle for Stoves or the like, of which the following is a specification, reference being had to the accompanying drawing, forming a part hereof.

Fig. 1 is a plan view of a handle for stoves or the like embodying my new design;

Fig. 2 is a front elevational view thereof;

Fig. 3 is an end elevational view thereof; and

Fig. 4 is a sectional view on line 4—4 of Fig. 2 looking in the direction of the arrows.

I claim:

The ornamental design for a handle for stoves or the like, as shown.

KURT RETTICH.
